UNITED STATES PATENT OFFICE.

THORKEL L. BRANDVOLD, OF WASECA, MINNESOTA.

GRAIN-BINDER.

1,122,067.

Specification of Letters Patent. Patented Dec. 22, 1914.

Application filed November 22, 1912. Serial No. 732,888.

To all whom it may concern:

Be it known that I, THORKEL L. BRANDVOLD, a citizen of the United States, residing at Waseca, in the county of Waseca and State of Minnesota, have invented new and useful Improvements in Grain-Binders, of which the following is a specification.

This invention relates to grain binders, and it has particular reference to an improved draft attachment.

It is customary in grain binders to connect the tongue with the frame of the machine in advance of the bull wheel and relatively near the binder side of the machine. Sometimes the condition of the grain is such that the cutting apparatus is subjected to a peculiar and excessive strain in which event the cutting side of the machine is apt to sag behind. At other times, the condition of the grain is such as to particularly tax the binding mechanism in which event the binder side of the machine will sag behind.

The present invention has for its object to produce a simple and effective draft attachment which shall be connected with parts of the binder frame adjacent to the binding side and the cutting side, respectively, to enable both sides to be subjected to the draft.

With these and other ends in view which will readily appear as the nature of the invention is better understood, the same consists in the improved construction and novel arrangement and combination of parts which will be hereinafter fully described and particularly pointed out in the claim.

In the accompanying drawing has been illustrated a simple and preferred form of the invention, it being, however, understood that no limitation is necessarily made to the precise structural details therein exhibited, but that changes, alterations and modifications within the scope of the claim may be resorted to when desired.

In the drawing, Figure 1 is a top plan view of a draft attachment constructed in accordance with the invention. Fig. 2 is a side elevation of the same. Fig. 3 is a sectional detail view taken on the line 3—3 in Fig. 1. Fig. 4 is a perspective view showing the evener bar 6 detached.

Corresponding parts in the several figures are denoted by like characters of reference. The tongue 1 is connected with the binder frame A relatively near the binding side

of the latter by means of a hinge bolt 2 upon which the tongue may swing for adjustment in an approximately vertical plane. The tongue 1 is connected with the binder frame relatively near the cutting side of the latter by means of a brace 3 which likewise has a hinge connection with the frame by means of a hook and eye 4, 5. A bar 6 which constitutes an evener is pivoted on the tongue 1 by means of a pin or bolt 7. The evener bar 6 has at its outer end a shoulder or offset 8 and a rearwardly offset portion 9, said offset portion being provided with a series of apertures 10.

11 designates a bell crank, one arm of which is bifurcated, as shown at 12, while the other arm is provided with a series of apertures 13 corresponding with the apertures 10 in the offset portion 9 of the evener bar with which the said bell crank is adjustably connected by means of a pin or bolt 14. The bolt 14 is connected by a brace rod 15 with the eye or member 5 on the binder frame with which the rear end 80 of the brace 3 is also connected. The brace rod 15 includes a turn buckle 15', enabling the length of said brace rod to be varied to compensate for various adjustments of the bolt 14. The brace rod 15 extends across 85 the tongue 1 on which it is supported, thereby supporting the evener bar 6 and related parts approximately in the plane of the tongue and preventing said parts from sagging unduly. The outer end of the apertured limb of the bell crank is connected by a brace 16 with the pin or bolt 2 by which the tongue 1 is connected with the binder frame. The bifurcated arm 12 of the bell crank is adapted to receive an ordinary draft 90 equalizer whereby draft is applied to the machine.

As will be seen from the foregoing description, the tongue 1 and the brace 16 are connected with the binder frame relatively near the binding side, while the braces 3 and 15 are connected with the machine relatively near the cutting side. By shifting the location of the bell crank 11 relatively to the evener bar 6, the preponderance of draft may be shifted in the direction of the binding side or the cutting side, as may be required, the requisite adjustment being easily effected by simply removing the bolt 14 and replacing the same 105 after adjustment of the parts.

The device is simple in construction, eas-

ily installed; effective in operation, and it will not interfere with the adjustment of the tongue relatively to the binder frame which is necessary for the purpose of effecting proper adjustment of the cutting apparatus.

Having thus described the invention, what is claimed as new, is:—

- 10 A draft attachment for grain binders comprising, in combination with a binder frame, a tongue, a bolt whereby said tongue is pivotally connected with the binder frame for movement in a vertical plane, a diagonal brace connecting the tongue with the binder frame, an evener connected with and extending laterally from the tongue at the opposite side of the diagonal brace and having at its free end an offset portion provided with a series of apertures, a bell 15 crank mounted on the evener and having an arm provided with a series of apertures cor-

responding with the apertures of the offset portion, a fulcrum member adjustably engaging alining apertures in the offset portion of the evener and in the arm of the bell crank, a brace member adjustable as to the length thereof, said brace member extending across the tongue and connecting the aforesaid fulcrum member with the binder frame, and a diagonal brace connecting the apertured arm of the bell crank with the rear end of the tongue at its point of attachment to the binder frame, the other arm of the bell crank being bifurcated for the reception of a draft equalizer. 25 30 35

In testimony whereof I affix my signature in presence of two witnesses.

THORKEL L. BRANDVOLD.
